UNITED STATES PATENT OFFICE.

FLORIÁN KOZUMPLIK, OF CHICAGO, ILLINOIS.

WINDOW.

Application filed March 16, 1925. Serial No. 16,031.

This invention relates to windows capable of use in various structures.

Briefly stated, an important object of this invention is to provide a window consisting of a number of sections having novel means whereby the same may be fitted to or interlocked with the window frame and to each other to provide a substantially air-tight connection.

Also, an important object of this invention is to provide a window of the character specified which is of highly simplified construction, simple to adjust, and cheap to manufacture.

Other objects and advantages will be apparent during the course of the following description:—

In the accompanying drawing forming a part of this application and in which like numerals are employed to designate like parts throughout the same,

Figure 1 is a side elevation of the improved window, the view illustrating the inside of the window frame and the glass panes carried thereby.

Figure 2 is a vertical transverse sectional view through the improved window frame and window section.

Figure 3 is a detailed horizontal sectional view taken on line 3—3 of Figure 2.

Figure 4 is a detailed horizontal sectional view through the upper portion of the improved window.

In the drawing, wherein for the purpose of illustration is shown a preferred embodiment of the invention, the numeral 5 designates a window frame having stiles 6 and upper and lower rails 7 and 8, respectively.

The frames 10 of the lower sash have their outer edge portions rabbeted as indicated at 11 and interfit with the rabbeted portions 12 of the window frame, whereby to provide a three point contact between the sash and the window frame. By thus providing this three point contact between the window frame and the sash a substantially dust and airtight connection is provided. Suitable hinges 14 may be employed to hingedly connect the lower sash to the window frame and locks 16 are carried by the inner side of the lower sash to hold the sash in closed position. Figure 1 plainly illustrates that the locks 16 are provided with bolts which engage eyes or suitable keepers 18 which

may be carried by the lower rail 8 and by an intermediate cross member 20 of the same.

With reference to Figure 3, it will be seen that the inner rails of the sash are double-rabbeted as indicated at 24 and are interlocked to provide a multiplicity of bearing spaces by means of which the passage of air is effectively prevented. In addition to this, the inner rails of the sashes are provided with flanges 26 which overlap the inner stiles and therefore cooperate with the rabbeted portions in establishing a dust and air-tight connection between the parts.

Coming now to the description of the upper sash 30, it will be seen that the same is hingedly connected as indicated at 32 to the stiles 6 and are rabbeted as indicated at 36 for contact with the rabbeted portions of the same and the upper center member 38. Figure 4 illustrates that the rabbeted portions 36 by being arranged in the manner illustrated provide a three point bearing surface between each sash and the window frame.

Figure 4 also illustrates that one of the stiles of one of the upper sashes is provided with a flange or sealing strip 40 which overlaps the adjacent stile and therefore cooperates with the rabbeted connection between the parts in establishing and maintaining a dust and air-tight connection between the parts.

Figure 2 illustrates that the improved window consists of inner and outer sashes arranged in spaced relation and the upper outer sash may be held in place by fastening devices 44 while the lower sash may be held in place by fastening devices 46 of any suitable type.

In carrying out the invention the upper sash may be provided with rotatable locking lugs or fingers 43 which may be moved into locking engagement with the center post 38 whereby to hold the upper sash against outward movement.

Having thus fully described my invention what is claimed is:—

The combination with a frame having stiles, rails and horizontal and vertical intermediate members, inner and outer closures vertically hinged to said stiles and consisting of upper and lower sash having rabbeted edges, the edges of said stiles, said rails and said horizontal and vertical intermediate

members adjacent said sash being rabbeted for engagement with the sash whereby a plurality of contact surfaces between the sash and the frame are provided, the upper sash being engaged with said vertical rabbeted intermediate members and having sealing strips overlapping the meeting portions of the upper sash at points spaced from

the vertical intermediate members whereby to cooperate with the connection between the vertical intermediate members and the upper sash in providing a substantially air and dust-proof connection between the parts aforesaid. 15

In testimony whereof I affix my signature.

FLORIÁN KOZUMPLIK.
